Fig. 2

This technical drawing illustrates a vertical heat exchanger assembly. The main vertical structure (A2) contains two sections of vertical tubes (C6) supported by a grid (C7). The top section (C8) is connected to a horizontal pipe assembly (B3, B4, B5, B6, B7, B8) which includes a pressure gauge (B3), a valve (B4), and a flow control device (B5). The bottom section (C9) is connected to another horizontal pipe assembly (B9, B10, C1, C2, C3) which includes a valve (B9) and a flow control device (B10). Various valves and fittings (D1 through D7) are shown at the top and bottom connections. The drawing uses a combination of line work and cross-hatching to indicate different components and materials.

UNITED STATES PATENT OFFICE

LOUIS D. KENSIG, OF WESTERN SPRINGS, ILLINOIS, ASSIGNOR TO NATIONAL ALUMINATE CORPORATION, OF CHICAGO, ILLINOIS, A CORPORATION OF ILLINOIS

APPARATUS FOR CONTINUOUS BLOW DOWN FOR BOILERS

Application filed August 9, 1928. Serial No. 298,422.

My invention relates to improvements in apparatus for continuous blow down of boilers and the like and has for one object to provide a new and improved blow down apparatus wherein the amount of water blown down by any one or all of the boilers in the battery whether working together or separately is automatically controlled. Another object is to provide means whereby the amount of blow down water leaving the boiler is automatically correlated and controlled by and with the amount of feed water entering the boiler. Another object is to provide means in coordination with the automatic control of each individual boiler for controlling the total amount of blow down water leaving the system. Other objects will appear from time to time in the specification and drawings.

My invention is illustrated more or less diagrammatically in the accompanying drawings wherein—

Figure 1 illustrates a battery of boilers with heat exchanger, pre-heater and injector;

Figure 2 is a section through the heat exchanger showing manual boiler control in elevation;

Figure 3 is a section through the automatic control valve;

Figure 4 is a side view of the automatic control valve.

Like parts are indicated by like characters throughout.

A A¹ are two of the battery of boilers. A² is a heat exchanger, A³ is a feed water heater. A⁴ is a feed water pipe leading to the injector A⁵ and thence to the discharge pipe A⁶ from which lead branches A⁷ A⁸ to boilers A A¹ respectively, controlled of course by the valves A⁹ which may be turned off when the boiler is out of operation.

Discharging from each of the boilers at a point just below the water line are blow off pipes B B. These pipes lead to and are controlled by automatic valves B¹, which valves are responsive in their operation to the inflow of feed water as will hereinafter appear and control the amount of water running off from the boiler. Pipes B² B³ lead from these valves to the blow off manifold B⁴. This blow

off manifold is controlled by and adjustably loaded continuous blow down valve B⁵, and extends into the heat exchanger tank B⁶, there being a plurality of discharge orifices B⁷ through which the water from the manifold B⁴ is discharged into the tank B⁶ at a number of points. Leading from the bottom of this tank is a run off pipe B⁸ controlled by a constant pressure valve B⁹. This pipe extends into the heat exchanger tank B⁶ and is provided with a series of perforations B¹⁰ so as to draw water off from the bottom of the tank at a number of points thereby permitting free and easy straight line flow of the hot blow down water from the top to the bottom of the tank. The pipe B⁸ discharges to the sewer and the foul blow off water is wasted therethrough.

The heat exchanger tank is flanged at the top as at C, at the bottom as at C¹. C² is a tube sheet, C³ a flanged water drum, the drum flange, the tube sheet and the tank flange C¹ are all fastened together so that a closed make up feed water chamber C⁴ is provided at the bottom of the tank B⁶ adapted to receive cold make up feed water from the pipe C⁵. Straight heat exchanger tubes C⁶ are mounted in the tube sheet C² and at their upper ends are also mounted in a tube sheet C⁷ which is flanged as indicated to engage a bonnet C⁸ which in turn communicates with a hot water make up pipe C⁹ passing out through the wall of the tank B⁶ and leading to the feed water heater. This pipe is flanged as at C¹⁰ and there is a packing C¹¹ to make a water and steam tight joint where the pipe passes out from the tank.

It will be noted that the flange C⁷ and the bonnet C⁸ are free from contact with the inner walls of the tank B⁶ and water may circulate about the flanges and the water level in the heat exchanger tank will be above the bonnet C⁸ and pipe C⁹. D is a float supported by the water in the vapor chamber D¹ formed in that part of the tank B⁶ above the tube sheet and above the bonnet C⁸ and pipe C⁹. This float D carries a valve stem D² upon which is mounted a valve D³ working in opposition to a seat D⁴ in the top D⁵ of the tank. The link D⁶ guides the valve

stem toward and from the seat D⁴. The vapor pipe permits discharge of vapor or steam from the vapor chamber D¹. When the water line is as shown in the figure the 5 float is down low enough to permit opening of the valve D³ and vapor can pass out through the vapor pipe D⁷ to be discharged into the feed water heater. If the water level in the tank B⁶ rises, the float will be lifted 10 and close the valve thus preventing discharge of water through the vapor pipe.

Experience shows that different boilers for some reason or other require different rates of blow off, therefore the operator by testing 15 the water in the individual boilers can ultimately arrive at a proper setting of the variable orifice control for each boiler.

If we say for instance we have 150 pounds boiler pressure, the pressure in the line beyond the variable orifice control will perhaps be 145 pounds. The spring loaded blow down valve B⁵ may be set to control the blow off and bring the pressure down to five or ten pounds gauge. This water flows into the 25 heat exchanger. Most of its passes down along the heat exchanger tubes giving up its heat to the cold incoming feed water, passing the constant pressure valve which for instance will be set at three pounds static 30 head and is discharged to the sewer. Above the bonnet at the top end of the heat exchanger tank will be some of the blow off water. The pressure in the tank will be to from two to five pounds or even less. When 35 the water at boiler pressure and temperature is discharged through the blow down valve into the heat exchanger tank at pressure but slightly above atmospheric as above indicated the sensible heat of the water is 40 dissipated in the production of water vapor which passes off from the blow down water into and from the vapor chamber and experience shows that the water vapor thus discharged amounts by weight to from fifteen to twenty percent or sometimes even 45 more of the blow down water depending upon the boiler pressure carried, the greater the boiler pressure, the greater the percent of vapor. This vapor passes out through 50 the pipe from the vapor chamber and since it is pure steam without impurities may be used for any purpose for which low pressure steam is desired as for instance for industrial purposes or for addition to the make 55 up water.

The cold water passing in at the bottom of the tank comes up through the heat exchanger tubes traveling in a direction opposite to the blow off water, is heated by the blow off water 60 and discharged ultimately to the feed water heater in the form of partially heated water.

The heat of the blow off water is thus used in two ways in connection with the make up water. The heat is used when the pressure is 65 reduced to cause vaporization. The vapor

passes off and is used. An appreciable amount of heat is thus saved and pure or distilled water is thus provided from the blow off water, the temperature dropping from boiler temperature down to approximately 70 212° at the heat exchanger tank.

The remaining blow off water at approximately 75 212° passes down toward the discharge coming in contact with and surrounding the pipes containing the make up water and giving up its heat to the point where the blow off water as it leaves the tank is but slightly warmer than the make up water as it enters the tank.

The automatic control valve is the same for each of the boilers and a description of one will suffice for all. The feed water enters the housing in the direction of the arrow X shown in Figure 3. It lifts the poppet valve F against the compression of the spring F¹ 80 permitting the flow of feed water through the valve. The upward movement of the valve F carries with it the valve stem F² and this lifts the blow off needle valve F³ away from its seat F⁴ to permit blow off water to run out in the direction shown in the arrow Y. The movement of the valve F in response to flow of feed water may be controlled by tension of the spring F¹ and the relation of the two valves may be adjusted by changing 85 the size of the valve parts or by providing different length valve stems. This adjustment is made once and for all and is made with or soon after the original set up of the boiler, and so no provision is provided or needed for change in adjustment during the 90 operation of the boiler plant.

The reason for this is that experience shows that tests made of the boiler at an early stage 95 show just what relation is required between blow off and feed water. Once that is established and the automatic valve adjusted for that purpose no further change is required.

Where I have used the term "valve" in the 100 specification and claims it will be understood that the term is used in a very broad and general sense and does not imply actual, positive, complete closure or shutting-off or arresting of flow of water. The structures that I have used are valves in the generally accepted commercial sense, but they do not have to and ordinarily never actually do prevent water flow; these valve structures merely control the rate of flow and may be so adjusted, operated and set as to do this, and so as to maintain the desired relation between inflow and outflow of the water in the various situations where these valves are placed for the purpose of carrying out my invention.

I have illustrated a spring-loaded valve and have so described it but it will be understood that by the use of the term "spring" as applied to the loading of the valve, I do not intend to be limited to a mere mechanical coil spring as illustrated. Any element hav- 125 130

ing a spring effect, no matter how that spring or yielding resistance to valve movement is effected, is a spring loading means for the valve in the sense in which I use the term.

5 I claim:

1. In combination, a boiler, a feed water pipe, and a blow off pipe for the boiler, a valve adapted to control the rate of flow through the blow off pipe, a member in the

10 feed water pipe so interposed in the path of the feed water as to be displaced according to the rate of flow of the feed water, said member being so directly connected to the valve in the blow off pipe as to control the rate of flow of the blow off water.

2. In combination, a boiler, a feed water pipe, and a blow off pipe for the boiler, a valve adapted to control the rate of flow through the blow off pipe, a member in the

20 feed water pipe so interposed in the path of the feed water as to be displaced according to the rate of flow of the feed water, said member being so directly connected to the valve in the blow off pipe as to control the

25 rate of flow of the blow off water, a heat exchanger into which the blow off water is discharged, and through which the feed water is fed, means for positively forcing feed water through the pipe and a separate control

30 valve interposed between the boiler and the member in the path of flow of feed water.

3. In combination, a plurality of boilers, a feed water pipe, branches leading from it to each boiler, means for forcing feed water to

35 and through said pipe, a blow off pipe for each boiler, a separate valve associated with the blow off pipe from each boiler to control the blow off therefrom and a member located in each branch of the feed water pipe leading

40 to a boiler adapted to be displaced by the flow of feed water in each branch there being a direct mechanical connection between the member in the feed water pipe branch and the blow off pipe associated with each individual

45 boiler whereby displacement of the member in the feed water pipe branch displaces the blow off valve of each boiler to control the blow off from each boiler in consonance with the rate of flow of the feed water of each

50 boiler, yielding means adapted to hold both the blow off valve and the member in the feed water pipe branch of the same boiler in closed position, said yielding means adapted to be overcome by a predetermined pressure of feed

55 water to lift the member in the feed water pipe off its seat to permit flow of feed water.

4. In combination with a boiler, a feed water pipe and a blow off pipe, a manually adjustable control valve in each, an automatic-

60 ically controlled valve in the blow off pipe, and a vane located in the feed water pipe adapted to be displaced by the flow of feed water, a direct mechanical connection between the vane located in the feed water pipe and the said automatically controlled valve in the

blow off pipe whereby movement of the vane in the feed water pipe responsive to the flow of feed water causes displacement of the blow off valve.

Signed at Chicago, county of Cook, and 70 State of Illinois, this 7th day of August, 1928.
